United States Patent Office

Des. 208,349
Patented Aug. 15, 1967

208,349

LAWN SPRINKLER

John D. Beinert, Babylon, N.Y., assignor to International Patent Research Corp., New York, N.Y., a corporation of New York

Filed Nov. 15, 1966, Ser. No. 4,667

Term of patent 7 years

(Cl. D91—1)

FIG. 1

FIG. 2

FIG. 3

FIG. 4

FIG. 1 is a perspective view of a lawn sprinkler showing my new design;

FIG. 2 is an enlarged fragmentary side elevational view thereof;

FIG. 3 is a cross sectional view taken on line 3—3 of FIG. 2;

FIG. 4 is a cross sectional view taken on line 4—4 of FIG. 2;

FIG. 5 is a top plan view of FIG. 2; and

FIG. 6 is a bottom plan view of FIG. 2.

The dominant portions of the design are those shown in solid lines.

I claim:

The ornamental design for a lawn sprinkler, as shown and described.
